[57] CLAIM

The ornamental design for a frame bar for constituting a frame structure, as shown and described.

DESCRIPTION

FIG. 1 is a front elevation of a frame bar for constituting a frame structure, showing a first embodiment of my new design, the rear elevational view being a mirror image of the side shown;

FIG. 2 is a top plan view thereof, the bottom plan view being a mirror image of the side shown;

FIG. 3 is a side elevation thereof, the opposite side being a mirror image of the side shown;

FIG. 4 is a perspective view thereof;

FIG. 5 is a front elevation of a frame bar for constituting a frame structure, showing a second embodiment of my new design, the rear elevational view being a mirror image of the side shown;

FIG. 6 is a top plan view thereof, the bottom plan view being a mirror image of the side shown;

FIG. 7 is a side elevation thereof; the opposite side being a mirror image of the side shown;

FIG. 8 is a perspective view thereof;

FIG. 9 is a front elevation of a frame bar for constituting a frame structure, showing a third embodiment of my new design, the rear elevational view being a mirror image of the side shown;

FIG. 10 is a top plan view thereof, the bottom plan view being a mirror image of the side shown;

FIG. 11 is a side elevation thereof; the opposite side being a mirror image of the side shown; and,

FIG. 12 is a perspective view thereof.

The frame bar for constituting the frame structure has been broken away in FIGS. 2, 3, 4, 6, 7, 8, 10, 11 and 12 to indicate indeterminate length.
